UNITED STATES PATENT OFFICE.

FRED GRUNDLER, OF CLEVELAND, BENJAMIN F. KUHN, OF SHAKER HEIGHTS, GRANT PHILLIPS, OF CLEVELAND, AND NORMAN A. FERRIER, OF LAKEWOOD, OHIO, AS-ASSIGNEES TO THE NEW YORK CENTRAL RAIL ROAD COMPANY, OF CLEVELAND, OHIO, A CORPORATION OF OHIO.

DEVICE FOR REMOVING CORE ENDS.

Application filed January 15, 1926. Serial No. 81,462.

Our invention relates to devices for removing the end or ends of cylindrical tubular members used as cores upon which flexible sheets such as paper are wrapped.

- 5 It has been found particularly useful in connection with the removal of the damaged end or ends of the cores upon which newsprint, i. e., the paper used for the production of newspapers, is wrapped.
- 10 As is well known, these rolls of paper are very heavy and the ends of the heavy paper fiber tubular cores are provided with sheet metal ferrules which are used to form seats or bearings for stub axles forming that part
- 15 of the printing press upon which the paper roll is mounted during the printing operation.

These ferrules often become damaged or deformed during shipment of the rolls and must be repaired or replaced before such rolls can be mounted in the press. In such cases the consignor or other agency responsible for the damage is under obligation to repair such damage before final acceptance

25 by the purchaser or consignee. Such repairs, in addition to the cost of additional handling and transportation, also involves unrolling of the paper, provision of a new core, and rewinding of the sheet. This involves a considerable expense, as will be apparent.

The object of our invention is to reduce such added expense to the responsible party by a simplification of the procedure in the

35 repairs.

This we accomplish by cutting off the end portions of a damaged core while the paper remains in place rolled up thereon and then substituting a temporary and reusable device which provides the required bearings or seats for the stub axles previously referred to.

Our present invention therefore consists of a device for removing the core ends and a method involving such removal and the substitution of the reusable bearing members.

The said invention consists of means and a method hereinafter fully described and particularly set forth in the claims.

The annexed drawings and the following description set forth in detail certain means for carrying out our invention, the disclosed means, however, constituting but one of the various mechanical forms in which the principle of our invention may be employed.

In said annexed drawings:

Fig. 1 represents a fragmentary axial section of a newspaper roll showing a deformed core end, in this instance bent into an elliptical form so as to preclude the practicability of straightening it so as to properly receive the stub axle.

Fig. 2 represents an end elevation of the structure shown in Fig. 1.

Fig. 3 represents a view similar to that of Fig. 1, showing the cutting device in place and in axial section.

Fig. 4 represents an end elevation of the cutting device.

Fig. 5 represents a fragmentary axial section of the roll after the one core end has been removed.

Fig. 6 represents a section taken upon the plane indicated by line VI—VI, Fig. 3.

Fig. 7 represents a section taken upon the plane indicated by line VII—VII, Fig. 3.

Fig. 8 represents a detail in perspective showing the slide upon which the rotatable cutter is mounted.

Fig. 9 represents a detail in perspective of the adjusting wedge forming a part of the device.

Fig. 10 represents a front elevation of a complete roll partly in axial section and showing the substitute and reusable bushing member forming the seats for the reception of the stub axles.

The cutting device illustrated includes a main or body portion 1 of general cylindrical form whose outer cylindrical surface 2 forms a bearing for the loosely mounted sleeve 3 whose outer surface 4 is frustoconical, the major diameter being at the outer end portion of the body member. The latter is provided with a circular plate 5 forming a flange of larger diameter than the interior end diameter of the core and which is secured to the main part of the body member by means of suitable screws such

as cap-screws 6-6. However, this flange might be made integral with the main portion of the body member.

This latter is formed with a longitudinal slideway 7, the inner portion of which is formed by a projection 8, Fig. 3. In this slideway is seated an adjusting member 9, whose inner portion forms a wedge 10, the outer portion forming a threaded member 11 which passes through an aperture 12 formed in the flange, and of substantially the outer diameter of the threaded member. The latter also passes through a recess 13 formed in a handle 14 which is secured in place by the said cap-screws 6-6, as shown in Fig. 4.

The inner end of the main part of the body portion is formed with a transverse dove-tailed slideway 1', Fig. 6, in which is seated a correspondingly formed slide 15, Fig. 8. This slide is provided at its outer end portion with a slot 16 and transverse apertures 17-17 which receive a journal pin 18 upon which is loosely mounted a rotatable circular cutter 19. The inner end of the slide 15 is provided with a bearing boss 20 which rests upon the inclined surface 21 of the wedge 10. An adjusting nut 22 is mounted upon the threaded member 11 and bears against the handle 14 as shown in Fig. 3.

This wedge member may be backed inwardly so as to permit the device to be inserted in the interior of the damaged end portion 23 of the core 24, as shown in dotted lines in Fig. 3. The outer minor diameter of the sleeve 3 is made such that it may be jammed into this end portion until the flange 5 comes in contact with the outer end of the sheet metal ferrule 25 with one of which each of the end portions of the core is ordinarily provided for reinforcement purposes.

The device having been so inserted into the core, the sleeve 3 acts as a bearing for the main body portion of the cutter and the latter may be manually rotated by means of the handle. By now screwing up the nut 22, the wedge 10 may be caused to engage the inner end of the slide 15 and cause the cutter to engage the inner portion of the core.

The length of the core is made such that the cutter will reach inwardly beyond what experience may indicate is the maximum length of the damaged end portion of such core, as will be understood.

By continuing the rotation and periodically screwing up the nut 22, it will be seen that this outer damaged end portion of the core may be finally severed and removed as shown in Fig. 5, leaving the main portion of the core in place. The extension 8 acts as a backing for the slide during the operation.

The other end of the core, whether damaged or not, is removed in a similar manner.

65 A substitute device is now inserted to take

the place of the removed end portion and ferrule 25 which latter was originally designed to form the recess or seat for the stub axles of the press. These ferrules are usually formed with a recess 26 which receives a key (not shown) formed or secured on the corresponding stub axle and which prevents the latter from turning in the ferrule. This key structure is provided so that a brake may be applied to such stub axle and the braking action transmitted to the roll during printing, as is well known to those skilled in the printing art.

The substitute device includes two bushing members 27-27, each of which is formed with an inner frusto-conical end portion 28 capable of ready insertion into the core, an outer frusto-conical end portion or socket 29 and an intermediate cylindrical portion 30. The portion 29 forms a shoulder 31 adjacent the cylindrical portion 30. The said portion 29 furthermore is formed with the cylindrical recess or seat 32 which is adapted to receive the stub axle and of the same size as the seat which was originally formed in the ferrule and is also formed with the key recess 33 corresponding with the recess 26 of the ferrule.

The outer diameter of the cylindrical portion 30 is made such as to make a tight fit 95 with the normal bore of the core.

The outer surface of the socket end portion of the bushing is made frusto-conical as shown, the major diameter being at the outer end. This major diameter is made such that 100 this end frusto-conical surface will jam into the interior of the aperture in the paper roll formed by the removal of the severed part of the core.

Each of these bushings is also formed with a longitudinal bore 34 through each of which passes the reduced end portion 35 of a tension rod 36. The outer ends of the latter are threaded as at 37 and receive the tightening nuts 38.

After the previously described severing operation has been completed and the severed core end-portions removed, one of the bushing members is driven or pushed by hand into the interior of the one end of the remaining part of the core until the shoulder 31 engages the other end of such core. The rod 36 is then slipped into the core from the opposite end, inserted into the bore 34 of the bushing member which is in place at the other end and the nut 38 then screwed upon the projecting end of the reduced end portion 35 of said member. The other bushing member is then slipped upon the opposite end of the rod, jammed into the interior of the core and its nut placed thereon. By screwing up one or both nuts, therefore, it will be seen that the two bushing members will be drawn toward each other and held in place by a continuously applied force holding the bush-

ing members against the ends of the core, and the inner ends of the said members being in contact with the shoulder 36' formed by the reduced end portion of the rod 36, the shoulders 31 being in contact with the ends of the core. The roll is then ready for insertion in the press.

What we claim is:

1. In a device of the class described, the combination of a main rotatable member; a cutter mounted upon said main member and movable radially with respect thereto; means for adjusting said cutter axially with reference to said main member; and a bearing sleeve; said main member being formed with an exterior journal surface upon which said sleeve is rotatably mounted.

2. The device described by claim 1 and in which the exterior surface of the bearing sleeve is frusto-conical.

3. The device described by claim 1 and in which the cutter is mounted beyond the bearing sleeve and upon the inner end of said main member; and the outer end of the latter is provided with a flange in contact with said sleeve; whereby said sleeve is located between said flange and inner end of the main member.

Signed by us this 30th day of December, 1925.

FRED GRUNDLER.
